HANDBAG

William O. Mann, Puente, Calif.

Application July 27, 1956, Serial No. 42,426

Term of patent 3½ years

(Cl. D87—3)

Fig. 1 is a perspective view of the handbag as seen from the front and one side thereof showing my new design; and

Fig. 2 is a perspective view showing the back and side of the handbag opposite that shown in Fig. 1.

The essential features of my design reside in the portions shown in solid lines in the drawing.

I claim:

The ornamental design for a handbag, substantially as shown and described.
